UNITED STATES PATENT OFFICE.

NAT. H. ELLIS, OF GREENVILLE, SOUTH CAROLINA, ASSIGNOR OF ONE-HALF TO JOSEPH E. LEACH AND ONE-HALF TO F. G. BUNKER, BOTH OF GREENVILLE, SOUTH CAROLINA.

PICKER-STICK CHECK.

Application filed November 3, 1921. Serial No. 512,540.

To all whom it may concern:

Be it known that I, NAT. H. ELLIS, a citizen of the United States, residing at Greenville, in the county of Greenville and State 5 of South Carolina, have invented new and useful Improvements in Picker-Stick Checks, of which the following is a specification.

This invention relates to picker checks for looms, and more particularly to checks 10 of that type in which a looped strap of leather or similar material is mounted on the lay near its outer end, the picker-stick moving within and longitudinally of the loop. These check-straps, from the inter- 15 mittent and rapidly recurring blows of the picker-stick thereagainst, wear rapidly and then break, necessitating replacement. This is an item of considerable expense, especially in large mills where many looms are run- 20 ning, and the present invention has for its object to reduce this expense by providing a means by which a broken strap may be coupled in such a way that it is capable of further use, the coupling means being so 25 arranged and mounted that they do not interfere with the picker-stick or any other parts, nor in any way impede or interfere with the ejection of a spent bobbin when 30 the invention is applied to a loom of the automatic filling-replenishing type.

The invention also has for its object to provide a securing or coupling means for the ends of a check-strap which permits the use 35 of a strap considerably shorter than the straps ordinarily used at the present time. The check straps now in use have a length of twenty-two inches, whereas the invention permits the use of a strap only eighteen inches in length, which saves four inches of 40 leather on each strap and therefore materially reduces the cost of the check-strap equipment.

The invention also permits the use of a two-piece strap, and by having one of the 45 pieces short and at that end of the loop where the strap usually breaks, the strap can be rendered capable of further use at very little expense by merely removing the short broken section and replacing it with a new 50 section.

The objects stated are attained by means

of a novel combination and arrangement of parts to be hereinafter described and claimed, and in order that the same may be better understood, reference is had to the accompanying drawing, wherein:

Figure 1 is a front elevation of the lay of a loom showing the application of the invention; Fig. 2 is a rear elevation thereof; Figs. 3 and 4 are cross-sections on the lines 60 3-3 and 4-4, respectively, of Fig. 2; Fig. 5 is an enlarged horizontal section on the line 5-5 of Fig. 3, and Fig. 6 is an elevation of a strap coupling member.

Referring specifically to the drawing, 10 65 denotes the lay of a loom without the shuttle box, the latter not being illustrated as it is not necessary for an understanding of the invention. On top of the lay is mounted the usual race plate 11. The picker stick 12 70 traverses the slot in the lay behind the front guide 13 which is bolted at one end, as shown at 14, to an ear 15 on the casting which forms the race plate 11. The bolt hole 16 in the guide 13 through which the bolt 14 75 passes, is elongated in the direction of the length of the guide to permit longitudinal adjustment. The other end of the guide 13 is opposite the upper end 17 of the lay-sword, and on its inner face as best seen in Fig. 4, is a lug 18 having a threaded aperture to take the inner end of a screw bolt 19 which passes through a lug 20 on the part 17 and is provided with a lock nut 19a. At 21 is shown one of the bolts by 80 which the upper end 17 of the lay-sword is secured to the lay 10. The parts of the guide 13 and the upper end 17 of the lay-sword which are connected by the bolt 19 are spaced, and in said space is mounted a buffer 22 for the picker stick 12, said buffer being composed of several layers of leather 85 through which the bolt 19 passes, said buffer being also centered on the lug 18. On the bottom of the guide 13, at the site of the buffer 22, is an inturned flange 23 on which the latter seats, said flange therefore serving to retain the buffer in place. On the last-mentioned end of the guide is also the deflecting plate 24 for the spent or rejected 90 bobbins.

The looped check-strap within which the

picker-stick 12 operates is composed of two sections 25 and 25^a. These two sections are made up of an old check-strap which has been broken. The break almost invariably occurs at the forward end of the loop, and the strap when broken is left in two pieces, one of which is longer than the other. Fig. 5 shows these two pieces, the short piece being shown at 25 and the long piece at 25^a. At the place where the break occurred, the two strap sections are lapped and united by a bolt 26 secured by a nut 27 the latter being on the outside, and the bolt head on the inside.

Under the nut 27 is placed a washer 28. The other ends of the strap sections are brought together and united by a coupling member consisting of a base plate 29 having projecting end wings 29^a provided with holes for bolts 30 on which are screwed nuts 30^a, one end of the strap is placed against the outer face of one wing and the other strap end is placed against the other wing, and the two ends are secured by the bolts 30, the latter passing therethrough. One strap end has an elongated bolt hole 31 to permit a limited lengthening or shortening of the loop, and under the nut of the bolt which passes through this hole is a washer 31^a. Under the nut of the bolt which secures the other strap end is also a washer 32, as well as a plate 33 extending along the back of the strap for a short distance. The purpose of the plate 33 is to prevent the check strap from flapping against the picker-stick 12 and thereby cause the head of bolt 26 to strike the side of the stick.

In the outer face of the plate 29 is a vertical groove 34 in which seats a depending bracket arm 35 carried by the lay 10, and secured to the latter in any suitable manner, a bolt 36 being shown. The plate 29 is longitudinally slotted as shown at 37 to take a bolt 38 whereby it is secured to the arm 35, the slot permitting adjustment of the plate in the direction of the length of the lay 10 as well as the length of the looped strap.

The assembly of parts just described is on one side of the loop formed by the strap sections 25 and 25^a, and on the opposite side of the loop are located the check-strap friction and guide fingers 39 and 40 between which the strap section 25^a works. The finger 39 is carried by the guide 13 and depends therefrom, and on said guide is a horizontal bracket plate 41 which carries the depending finger 40, the latter having at the top a plate-like enlargement 42 which seats against the bottom of the plate 41, said contiguous parts being grooved and ribbed, respectively, as shown at 43 in Fig. 1. A bolt 44 passes through the parts 41 and 42, and by means of a nut 45 screwed on the bolt, said parts are rigidly connected. The part 41 is slotted, as shown at 46, and the part 42 also has a slot 47 for the bolt 44. These bolt slots run

in a direction transverse of the strap loop, and their purpose is to permit the finger 40 to be advanced or retracted with respect to the finger 39, and so adjusted that it will not press the check strap against the picker-stick. The fingers 39 and 40 take up less room, and they are set back from the bobbin-deflecting plate 24 farther than the ordinary check-strap friction devices now in use.

In order that the nut 27 may pass the back of the deflecting plate 24 without striking the same, said plate has been set forwardly a bit from the side of the picker stick 12. This relocation of the plate 24 does not interfere with its proper function of guiding the spent or ejected bobbins for the reason that it is formed at the top, at one end, with a lug or enlargement 24^a which catches the end of the bobbin and keeps the same from dropping between the picker stick 12 and the buffer 22. The face of the plate 24 also has an oblique rib 24^b which turns the big end of the bobbin downwardly to assure its delivery to the can or other receptacle into which the spent bobbins drop.

Ordinarily, a check strap has a length of twenty-two inches, whereas with the coupling member 29 it is possible to use a strap having a length of eighteen inches, so that a saving of four inches of leather is effected. It will be noted that the member 29 couples the strap ends without the same being lapped, and this arrangement permits the use of a shorter strap. The coupling means in use at the present time require that the twenty-two inch strap be overlapped four inches.

The coupling member also permits the use of a strap which is in two sections, one section being shorter than the other. This short section needs to be only six inches long, and it will be placed at that end of the loop where the break usually occurs. It will therefore be seen that when the short section breaks it can be cheaply renewed.

The invention has been illustrated in connection with a certain type of automatic filling-replenishing loom, but it will be understood that it is not limited to such, but may, with equal facility, be applied to any looms of this or any other type, by a proper adjustment of the parts whenever necessary.

I claim:

1. The combination with the lay of a loom; of a picker check consisting of a strap composed of pieced sections, a plate to the outer face of which the strap ends are secured for maintaining the strap in looped form, and a guard plate extending along side the loop at one end thereof on the outside of the strap.
2. The combination with the lay of a loom; of a picker check consisting of a looped

strap, a plate to the outer face of which the strap ends are secured for maintaining the strap in looped form, said plate being located on one side of the loop, spaced friction and 5 guide fingers on the other side of the loop, between which fingers the strap seats, the finger opposite the inner face of the strap being stationary, and the finger which is opposite the outer face of the strap being adjustable toward and from said inner finger. ¹⁰ In testimony whereof I affix my signature.

NAT. H. ELLIS.
